UNITED STATES PATENT OFFICE.

HENRY RICHARDSON, OF CHICAGO, ILLINOIS.

WIRE FABRIC.

1,095,521.

Specification of Letters Patent.

Patented May 5, 1914.

Application filed July 14, 1913. Serial No. 778,885.

To all whom it may concern:

Be it known that I, HENRY RICHARDSON, a subject of the King of Great Britain, residing at Chicago, in the county of Cook 5 and State of Illinois, have invented certain new and useful Improvements in Wire Fabrics, of which the following is a specification.

This invention relates to wire fabrics and 10 has reference more particularly to wire link fabrics of the kind at present extensively used to form the bottoms of beds, couches, and like articles of furniture.

More specifically, my invention relates to 15 that type of wire link fabrics which is characterized structurally by the use of parallel longitudinal rows of interconnected bent wire units or links that are connected transversely at intervals by wire cross links.

The main object of the present invention 20 is to provide a construction of this type characterized by a high degree of simplicity and economy of manufacture, and which, at the same time, will permit of the use of a 25 much smaller and lighter wire than has heretofore been practicable in articles of this character, thus reducing both the weight by effecting a very considerable reduction 30 of the article and its cost of manufacture in the amount of metal going into the same. This object I attain by a novel construction which permits the use of a much lighter 35 gage wire without involving any decrease or loss of the required tensile strength of the fabric to sustain the strains to which it 40 is subjected in service; and the novel structural feature whereby I secure this result resides mainly in the avoidance anywhere in the longitudinal strands of open hooks 45 or loops that are liable to pull out under strain, this being effected by anchoring the terminal portions of the wires forming such hooks or loops to the main tension member of the wire link or unit.

With this and other minor objects in view, 50 my invention resides in the novel fabric structure, and in the novel bent wire unit forming the basis thereof, substantially as hereinafter described and definitely pointed out in the claims.

A fabric representing a practical embodiment of my invention is illustrated in the accompanying drawing, in which—

Figure 1 is a top plan view of a portion 55 of a bed bottom frame equipped with my improved wire fabric, the latter being

broken out between its ends. Fig. 2 is an edge view of Fig. 1 as shown from the right of the latter figure, with the end bars of the frame appearing in cross section. Fig. 60 3 is a fragmentary top perspective detail view, somewhat enlarged, of the interconnected parts of two adjacent links of a strand, showing also the cross links; and Fig. 4 is a fragmentary bottom perspective 65 view of the parts shown in Fig. 3.

Referring to the drawings, 10 designates one of the longitudinal bars of the bed bottom frame, and 11 and 12 the end crossbars, united to the longitudinal bars by rivets 13. 70 The end bars 11 and 12 have upstanding flanges apertured as usual for the reception of the end hooks of the usual helical springs 14 and 15, through which the ends of the bed bottom fabric are commonly united with 75 the cross bars of the frame to furnish the desired resilience and elasticity.

Referring now to the fabric itself, in 80 which the novel features of the present invention reside, this fabric is made up, as to its longitudinal strands, of duplicate bent wires units, each of which in the preferred form here shown, comprises a two-ply tension member with a terminal loop joining the limbs of said two-ply tension member at 85 one end of the unit and a two-ply terminal loop at the other end of the unit having the terminal portions of the wires forming the same anchored to the tension member, the adjacent loops of adjacent units in each 90 longitudinal strand being interlooped; and the said longitudinal strands are then flexibly connected transversely by cross links which are hooked at their ends through the first mentioned terminal loops of the units 95 or links of the longitudinal strands.

Describing the structure somewhat more 100 in detail, and referring to the drawings, 16 and 17 designate straight, parallel lengths of wire constituting the two limbs of a two-ply tension member forming the main body portion of the unit. These limbs are connected at one end by an integral single-ply loop 18 that extends lengthwise of the unit. Preferably, and as herein shown, the limbs 105 16 and 17 are twisted together at the inner end or base of the loop 18, as shown at 18', to prevent spreading of said limbs and the sides of the loop 18 under transverse stretching strains, as well as to confine the 110 ends of the cross-links against displacement. At the other end of the member 16 the wire

is bent downwardly and thence upwardly across itself (Fig. 3) forming one member 19 of a two-ply loop at this end of the tension member, the wire extending thence directly across the lower end of the tension member and being thence turned under and clenched to the latter as shown at 20. At the same end of the member 17 the wire is similarly bent downwardly and thence upwardly across itself (Fig. 4), forming the other member 21 of the two-ply loop, the wire extending thence directly across the tension member in the opposite direction from the extension of loop 19 and being similarly bent beneath and clenched to the tension member as shown at 22. As will be observed by reference to Fig. 3, in the described formation the hooked terminal portion 22 of the loop 21 crosses the hooked terminal portion 20 of the loop 19.

23 designates the cross links which are simply short straight lengths of wire having hooked ends 24 (Figs. 3 and 4) that engage the terminal loops 18 of the units making up adjacent longitudinal strands.

The mode in which the units or links are connected up in the fabric is readily apparent from the drawing. The single-ply loops 18 of the transverse row of units at one end 30 of the fabric are engaged by the hooks of the adjacent row of helical springs, and the two-ply loops 19, 21 of the other transverse end row of units are likewise engaged with the hooks of the adjacent row of helical springs. 35 Between the end rows the single-ply loops 18 of each transverse row are interlooped with the two-ply loops 19, 21 of the next adjacent transverse row of units; and, as stated, the single-ply loops 18 formed in 40 adjacent longitudinal strands are flexibly connected by the cross links 23.

The described construction provides a fabric of the well known general type employing longitudinal strands and separate cross links connecting the same, but entirely dispenses with open hooks or loops in the longitudinal strands, thus permitting the use of a much lighter or finer wire than has heretofore been possible without any sacrifice of strength, owing to the secure anchoring of the terminal portions of the two-ply loop at one end of each tension member to the tension member itself. I have found by test that a fabric embodying the construction herein shown and described has a strength fully equal to that of a fabric employing double the weight of wire and similarly constructed except for the employment of hooks having free or unconnected ends in lieu of 55 the anchored two-ply loop of the present construction.

I claim—

1. A wire link fabric made up of integral bent wire units arranged in longitudinal and transverse rows, each of said units com-

prising a two-ply tension member, a loop joining the limbs of said two-ply tension member at one end of the unit, and a two-ply loop at the other end of the unit having the terminal portions of the wires forming the same anchored to said tension member, adjacent loops of adjacent units in the same longitudinal strand being interlooped, and cross-links flexibly connected at both ends to said first named loops of laterally adjacent units. 70

2. A wire link fabric made up of integral bent wire units arranged in longitudinal and transverse rows, each of said units comprising a two-ply tension member, a loop joining the limbs of said two-ply tension member at one end of the unit, and a two-ply loop at the other end of the unit having the terminal portions of the wires forming the same extended in opposite directions across and clenched to said tension member, adjacent loops of adjacent units in the same longitudinal strand being interlooped, and cross-links engaged with and connecting said first named loops of laterally adjacent 80 units. 85

3. A wire link fabric made up of integral bent wire units arranged in longitudinal and transverse rows, each of said units comprising a two-ply tension member, a loop joining the limbs of said two-ply tension member at one end of the unit, said limbs being twisted together at the inner end or base of said loop, and a two-ply loop at the other end of the unit having the terminal portions 95 of the wires forming the same extended across and clenched to said tension member, adjacent loops of adjacent units in the same longitudinal strand being interlooped, and cross-links engaged with and connecting said first named loops of laterally adjacent 100 units. 105

4. As an article of manufacture, an integral bent wire unit, comprising a two-ply tension member, a loop joining the limbs 110 of said two-ply tension member at one end of the unit, and a two-ply loop at the other end of the unit having the terminal portions of the wires forming the same anchored to said tension member. 115

5. As an article of manufacture, an integral bent wire unit, comprising a two-ply tension member, a loop joining the limbs of said two-ply tension member at one end of the unit, and a two-ply loop at the other end 120 of the unit having the terminal portions of the wire forming the same extended in opposite directions across and clenched to said tension member. 125

6. As an article of manufacture, an integral bent wire unit, comprising a two-ply tension member the limbs of which are twisted together at one end, a loop forming an integral extension of the twisted limbs 130 of said tension member, and a two-ply loop

forming an extension of the other end of said tension member, the terminal portions of the wires forming said two-ply loop being clenched to said tension member.

7. As an article of manufacture, an integral bent wire unit, comprising a pair of main longitudinal limbs, a cross connection between said limbs at one end of the latter, and terminal loops at the other ends of said

limbs respectively, the free end portions of 10 the wires forming said terminal loops being firmly secured directly to said main longitudinal limbs.

HENRY RICHARDSON.
